UNITED STATES PATENT OFFICE.

GEORGE MEADE CHARLES, OF CHICAGO, ILLINOIS.

FAUCET.

1,148,217.

Specification of Letters Patent. Patented July 27, 1915.

Application filed April 11, 1914. Serial No. 831,245.

To all whom it may concern:

Be it known that I, GEORGE MEADE CHARLES, citizen of the United States, residing at Chicago, in the county of Cook

5 and State of Illinois, have invented new and useful Improvements in Faucets, of which the following is a specification.

The invention relates to that class of faucets commonly used for drawing hot or 10 cold water, or a mixture of both and discharging the same through a common outlet; and it has for its chief object to improve the construction and efficiency of this 15 class of faucets, and to extend their usefulness to drawing water in varying quantities and of varying temperatures.

Other objects of the invention will become apparent upon a complete disclosure thereof.

20 The invention consists in providing the shell or case of the faucet with oppositely-disposed inlets, and a spring-pressed valve provided with peculiarly-shaped inlets arranged to register with either or both of 25 the shell-inlets, or to cut-off the flow of liquid therethrough, the valve being provided with a single or common outlet.

In the drawing Figure 1 is a central, vertical section, partly in elevation, of my improved faucet, showing the valve in position 30 to cut-off the supply of both hot and cold water; Fig. 2, a similar view, showing the valve in position to draw hot and cold water; Fig. 3 an elevation of one side of the 35 valve detached; Fig. 4, a similar view of the opposite side thereof; Fig. 5, a vertical section of the shell and valve, showing the valve in position to draw cold water; Fig. 6, a similar view, showing the valve in position 40 to draw hot water; Fig. 7, a top plan view of the faucet, and Fig. 8 a transverse section through the valve-ducts and the inlet-ports of the casing, in position to draw hot and cold water of unequal proportions.

45 Referring to the several views, the numeral 1 indicates the shell or case of the faucet provided with the usual valve-chamber 2, preferably of conical form, and with two oppositely-disposed inlets 3 and 4, each 50 inlet being internally screw-threaded to receive externally screw-threaded supply-pipes, not shown.

The lower portion of the shell is externally screw-threaded to receive a screw-threaded cap 5 which is centrally apertured 55 for the passage of a detachable discharge-

pipe or common outlet 6, said common outlet being provided with a beveled head 7 forming a seat for the valve 8, as shown in Figs. 1 and 2.

The upper portion of the shell is screw-threaded to receive a screw-threaded cap 9 which is centrally perforated for the passage of the valve-stem 10 of the valve, and is provided with marks 11 and 12, indicating 60 respectively the positions of the valve for drawing cold and hot water. The cap is also provided with marks 13 and 14 indicating the position of the valve for drawing mixtures of cold and hot water in varying 65 quantities and of varying temperatures.

The valve is provided with a chamber 15 communicating with the common outlet, said valve being provided with oppositely-disposed ducts 16 and 17 of peculiar shape 70 opening into said chamber 15, the duct 16 consisting of two apertures *a* and *b* connected by a passageway 18, preferably slightly curved, and the duct 17 consisting of a single aperture and an upwardly-inclined recess 19, the object of which recess and the connecting passageway will be hereinafter explained.

The valve-stem is provided with a suitable handle 20, by which the valve may be 75 turned to cause one or the other, or both ducts to register with the supply-inlets, or to close both of said inlets. The handle is provided with a pointer 21 to indicate the 80 position of the valve-ducts with respect to the marks indicating the temperatures of water to be drawn.

Situated between the solid head of the valve and the inner face of the cap 9 is a 85 spring 22, designed to hold the valve firmly to its seat on the head 7 of the detachable outlet or discharge-pipe, and if desired a ring-washer of suitable material may be interposed between the end of the valve and its seat.

The normal or closed position of the valve is indicated when the pointer is at the mark 12 which is the "off" position, and when it is desired to draw, say for instance, cold water, the handle is turned to move the pointer in the direction of the indicating-mark 11. When said mark is reached the aperture *a* of the duct 16 will be in register with the inlet 4, which is the cold water inlet, and the hot water inlet will be closed, 110 as shown in Fig. 5. Should it be desired to draw a mixture of cold and hot water of

equal proportions, the handle is turned to move the pointer toward the indicating mark 13, and when said mark is reached the aperture of duct 17 will be in register with the hot water inlet 3 and the aperture of duct 16 in register with the cold water inlet 4, as shown in Fig. 2. To draw hot water the handle is turned in the same direction until the pointer reaches the indicating mark 12, when the duct 17 will be in register with the hot water inlet 3, the cold water inlet being closed, as shown in Fig. 6. If it is desired to either control the quantity of water or to regulate the temperature thereof, the handle is manipulated to move the pointer to and fro between the indicating marks 13 and 14, when cold and hot water in varying proportions and degrees of heat may be drawn. In moving the pointer between the marks 13 and 14, the cold water will enter the connecting passageway 18 and pass through each aperture *a* and *b* of the duct 16 into the common outlet, mixing with the hot water which, entering the recess 19, will flow through the duct 17 as shown in Fig. 8, and as but a limited quantity of water can enter the passageway and the recess, it will be seen that the quantity of either the inflowing cold or hot water may be regulated, and the temperature increased or decreased, according to the position of the pointer between the marks 13 and 14.

Having thus fully described my invention what I claim, is—

1. A faucet, having in combination a chambered shell provided with oppositely-disposed inlets and a common outlet, a chambered valve having ducts arranged to register with the shell-inlets, one of said ducts comprising two separated apertures connected together by a shallow passageway, and the other comprising a single aperture

and a shallow recess leading thereto, and means indicating the several positions to which the valve may be turned to draw 45 different temperatures of water.

2. A faucet, having in combination a chambered shell provided with oppositely-disposed inlets and a common outlet, a valve having a chamber communicating with the common outlet and provided with ducts arranged to register with the shell-inlets, one of said ducts consisting of two apertures connected together by a passageway, and the other consisting of a single aperture and a recess leading thereto, and a shell-cap having marks thereon indicating the various positions to which the valve may be turned to draw cold and hot water in varying proportions. 60

3. A faucet, having in combination a chambered shell provided with oppositely-disposed inlets and a common outlet, a chambered valve in communication with the common outlet, said valve being provided with ducts arranged to register with the shell-inlets, one of said ducts consisting of two apertures connected together by a passageway, and the other consisting of a single aperture and a recess leading thereto, a shell-cap provided with marks indicating the several positions to which the valve may be turned to permit varying quantities of water of different degrees of heat to be drawn, a handle for turning the valve, and a pointer carried by the handle for indicating the position to which the valve is turned. 65

In testimony whereof I affix my signature in presence of two witnesses.

GEORGE MEADE CHARLES.
